UNITED STATES PATENT OFFICE.

CLYDE J. COLEMAN, OF NEW YORK, N. Y.

RAILWAY SIGNALING SYSTEM.

No. 916,674.

Specification of Letters Patent. Patented March 30, 1909.

Application filed July 10, 1908. Serial No. 442,815.

To all whom it may concern:

Be it known that I, CLYDE J. COLEMAN, a citizen of the United States, residing in New York, county and State of New York, have 5 invented certain new and useful Improvements in Railway Signaling Systems, of which the following is a specification.

My invention relates to electric railway block signaling and has for its object the 10 more efficient and economical arrangement of the signal controlling and signal operating circuits and apparatus.

I have shown my invention applied to a system in which the track rails are employed 15 for the signal controlling circuits and in which the source of power is an alternating current one, and I prefer to employ such a system, but my invention in its broader phase is not limited thereto.

20 Specifically my invention consists in the arrangement of circuits and apparatus whereby a signal may be controlled in accordance with the condition of a given length of track circuit without requiring that the signal controlling current be supplied at one end of the 25 circuit to a signal controlling relay at the other end of the circuit (which has certain disadvantages preventing its commercial use for some types of systems) and without requiring that relays at different parts of the 30 given length of track circuit should be connected by circuits extending the entire length thereof. Thus in the specific embodiment which I will hereinafter describe, 35 the source supplying the track is placed at the center of the block and the block limits are defined by bonds of negligible impedance connecting the rails.

Prior to this invention relays were placed 40 in operative relation with the track circuit at each end of the block and a separate circuit had to be supplied to connect these relays together so that if either opened the signal at the entrance of the block would go to danger.

45 According to my present invention, I preferably arrange the source of signal controlling current so as to supply the rails at about the center of a given length of rails. At one end of this given length of rails I place a relay 50 in operative relation to the rail circuit and this relay controls a signal operating circuit in the usual manner. At the other end of the given length of rails I place a second relay in operative relation to the rails and this 55 relay is arranged so that by its opening it will react upon the other relay to cause it to open,

this being effected in the specific instance herein described, by causing the relay at the exit end of the block by its opening to cause the introduction of an impedance into the 60 circuit of the track source, whereby the current supplied by the track source to the rails is so far reduced that the relay at the entrance end of the block will open just as it would when the track is short circuited by 65 the presence of the train. A train, therefore, in any part of the block will cause the signal controlling relay to open and place the signal to danger. In order that the relay at the 70 exit end of the block should again close when the train has left the block, the relay at the exit end may be made more sensitive than the relay at the entrance end, or it may be differently arranged with reference to the track, or, while normally of the same sensitiveness 75 as the signal controlling relay, it may, in accordance with my more specific invention, be arranged so that when it is opened it is given a specially strong field in order to make it more sensitive at that time and respond 80 readily to the presence in the track of the reduced signal controlling current.

Referring to the drawings, Figure 1 is a diagrammatic illustration of a signal block of a railway embodying one form of my invention. 85 Fig. 2 illustrates diagrammatically a modification of the relay at the exit end of the block.

A is a source of alternating current, which by transformer's or otherwise, may supply the current for any desired number of blocks and 90 also, if desired, may supply the power for operating the signal.

B, B' are the rails of one block, it being understood that other blocks may be mere repetitions of this block.

95 C, C' represent respectively the primary and secondary of a transformer, the primary being connected across the circuit of the generator A, while the secondary is connected across the rails at a central point in the 100 block. The current supplied by this track source divides so that part of it is carried through a circuit at one side of the source, including the rails and a bond of negligible impedance D, which bond short-circuits the 105 rails at this point and prevents any substantial current from passing to the rails of the next block, while the other circuit includes the rails and a similar bond D' at the other side of the source.

110 E, E' represent coils that are in inductive relation to the rails at each end of the block.

F is a relay having a movable coil f in the circuit of the track coil E, the relay being thus placed in operative relation to the rails B, B' at the entrance end of the block.

5 f' is a coil supplied by generator A independently of the rails, this coil magnetizing the field structure f². The relay when closed, due to the presence of current in the coil f supplied by coil E when current of sufficient 10 value is passing through the rails and the bond D, closes the circuit of the signal controlling magnet G and thereby moves the signal H to safety. Although no train is illustrated as being between the track source and 15 the bond D, the relay F is shown as opened placing the signal H at danger, because the train J is indicated as present in the other end of the block. This result is effected by the relay and circuits at the exit end of the 20 block which I will now describe.

F' is the relay at the exit end of the block. It is constructed and wound and supplied by current exactly the same as the relay F except that the arrangement should be such 25 that it will open when the electro-motive-force of the track source may be low enough to cause relay F to open. This may be effected in various ways, as for instance, by suitable design of the ampere turns of one or 30 both windings f, f' of the relay F', or by suitable design of the track coil E'; or by a location of the track source substantially nearer the exit than the entrance end of the block.

K is an impedance in series with the primary C of the track source, this impedance being short-circuited by conductor k when the relay F' is closed.

When no train is in the block, both relays are closed because the movable coils f' receive current from the respective track coils E, E'. The signal H will then be at the clear position. A train entering the block at the right hand end immediately short-circuits the current from the rails B, B', whereby the 45 coil f' of relay F becomes deenergized and the relay F is moved to the position shown so that the signal H assumes its danger position. When the train passes the track source it no longer short-circuits the current 50 from the rails at the right of source C' and soon after it passes the track source sufficient current would again flow in the coil E to close the relay F if it were not for the action of the relay F'. When, however, the 55 train is, as indicated in Fig. 1, in this portion of the block no current is supplied to the coil E' and therefore relay F' opens. The opening of this relay introduces the impedance K into the circuit of the primary C of the track source, whereby the electro-motive-force of the track source is substantially lowered, the impedance being of such value as to lower said electro-motive force sufficiently to reduce the current flowing to the entrance end of the block to such a point

that relay F will not close. When the train proceeds beyond the exit end of the block the relay F' closes because the system is so designed that the relay F' will respond to the current flowing in the track at the exit end 70 when the electro-motive-force of the source has been lowered by the insertion of the impedance K. As soon as relay F' closes impedance K is short-circuited and the electro-motive-force of the track source is raised to 75 such a point as will cause relay F to close and clear the signal.

In Fig. 2 I show a modified form of relay for the exit end of the block. The field of this relay is supplied by one or both of the 80 coils f³, f⁴, which receive their current from secondaries M' and N' of transformers whose primaries M and N are connected so that when the relay is closed the two primaries are in shunt to each other and in series with 85 the source C. When the relay is opened the primary N is cut out and the primary M is alone in the circuit of the primary C. The primary M is of much greater impedance than the primary N so that it acts as an impedance just as does the impedance K of Fig. 1 to reduce the electro-motive-force applied to the track. At the same time a much greater proportion of the energy of 90 this circuit is used in this primary M, causing its secondary to supply such a current to the coil f³ as to make the field of the relay much stronger when the relay is opened than when it is closed. The relay is in this manner caused to respond to relatively feeble 95 currents in the track circuit, while ordinarily a smaller amount of energy is consumed in the field of this relay.

I desire it to be understood that my invention is not limited to any mere details of 105 construction and arrangement which I have illustrated and described as many modifications may be made therein without departing from the principles of my invention as set forth in the appended claims.

What I claim as new and desire to secure by Letters Patent is:

1. In a railway signal system, a signal controlling circuit, a source of current feeding the same at a central point therein, two 115 relays one in operative relation to said circuit at each side of said source, means for causing one of said relays to open responsive to the opening of the other, and a signal operatively related to the first of said 120 relays.

2. In a railway signal system, the track rails, a source of signal controlling current supplying the same, relays operatively arranged with respect to the track rails and 125 said source, a signal arranged to be cleared by the closing of one of said relays, and means for maintaining said relay open when the other relay is open.

3. In a railway signal system, a signal 130

- controlling circuit, a source of current feeding the same, two relays in operative relation with said circuit at different points, means for causing one of said relays to open responsively to the opening of the other, and a signal arranged to be controlled by the first of said relays.
4. In a railway signal system, the track rails, a source of current feeding the same, two relays in operative relation with the track at different points, means for causing one of said relays to open responsively to the opening of the other, and a signal arranged to be controlled by the first of said relays.
5. In a railway signal system, a signal controlling circuit, a source of current feeding the same, a relay in operative relation to said circuit, a signal controlled by said relay, a second relay in operative relation with another part of said circuit, and means for causing the opening of said second relay to reduce the current supplied by said source to said circuit.
6. In a railway signal system, a signal controlling circuit, a source of current feeding the same, a relay in operative relation to said circuit, a signal controlled by said relay, a second relay in operative relation with another part of said circuit, and means for causing the opening of said second relay to reduce the electro-motive-force of said source.
7. In a railway signal system, a signal controlling circuit, a source of current feeding the same, a relay in operative relation to said circuit, a signal controlled by said relay, a second relay in operative relation with another part of said circuit, an impedance in series with said source, and a short-circuit around said impedance including the contacts of the second relay.
8. In a railway signal system, the track rails, a source of current supplying the same, a relay in operative relation with the track rails at one side of said source, a signal controlled by said relay, a second relay in operative relation with the rails at the other side of said source, and means for causing the opening of said second relay to reduce the current supplied to the track rails.
9. In a railway signal system, the track rails, a source of current supplying the same, a relay in operative relation with the track rails at one side of said source, a signal controlled by said relay, a second relay in operative relation with the rails at the other side of said source, and means for causing the opening of said second relay to reduce the electro-motive-force of said source.
10. In a railway signal system, the track rails, a source of current supplying the same, a relay in operative relation with the track rails at one side of said source, a signal controlled by said relay, a second relay in operative relation with the rails at the other side of said source, an impedance in series with
- said source, and a short circuit around said impedance including the contacts of the second relay.
11. In a railway signal system, the track rails, a source supplying the same, two relays in operative relation to the rails at opposite sides of said source, means for causing one of said relays to close with less current in the track rails than that required to close the other, a signal, a signal operating circuit controlled by one of said relays, and means controlled by the other of said relays for reducing the current supplied by said source.
12. In a railway signal system, the track rails, a source supplying the same, two relays in operative relation to the rails at opposite sides of said source, means for causing one of said relays to close with less current in the track rails than that required to close the other, a signal arranged to be cleared by the less sensitive relay, and an impedance in series with the track source arranged to be short-circuited by the more sensitive relay.
13. In a railway signal system, the track rails, a source supplying the same, two relays in operative relation to the rails at opposite sides of said source, means for causing one of said relays to close with less current in the track rails than that required to close the other, a signal arranged to be cleared by the less sensitive relay, and means controlled by the more sensitive relay for varying the electro-motive-force of said source.
14. In a railway signal system, the track rails, a source of current supplying the same, a signal, a relay controlling the same operatively arranged with respect to the track rails, a second relay controlling the electro-motive-force applied to the rails by said source in operative relation to the rails at the opposite side of said source, and means controlled by the second relay for increasing its own sensitiveness when it has decreased said electro-motive force.
15. In a railway signal system, the track rails, a source of current supplying the same, a signal, a relay controlling the same operatively arranged with respect to the track rails, a second relay controlling the electro-motive-force applied to the rails by said source and having relatively movable actuating coils one in operative relation to the track rails and the other supplied independently of the rail circuit, and means controlled by said relay for reducing the electro-motive-force applied by said source to the rails and simultaneously increasing the relative strength of its independently supplied coil.
16. In a railway signal system, the track rails, a source of current supplying the same, two relays in operative relation to the track rails, a signal controlled by one of said relays, two coils of different impedances and turns arranged to be controlled in the circuit of

said source by the other of said relays and means for causing the current in said coils to affect the action of said relay.

17. In a railway signaling system, the track rails, a source of current supplying the same, a relay having a coil arranged in operative relation with the rails, and means for producing a magnetic field to coact with said coil, two coils of different impedances and 10 turns normally in shunt with each other in series with said source, one of said coils being connected to the relay contacts, and means for relatively varying the magnetic field of said relay according to the circuit connections of said coils.

18. In a railway signaling system, the track rails, a source of currents supplying the same, a coil in operative relation with the rails, two other coils, a relay controlling the 20 connection of the last two coils relative to the source, and means for controlling the relay determined by the currents in all of said coils.

19. In a railway signaling system, the track rails, a source of currents supplying the same, a coil in operative relation with the rails, two other coils, a relay controlling the connection of the last two coils relative to the source, means for controlling the relay 30 determined by the currents in all of said coils, a second relay in operative relation with the rails, and a signal controlled by said second relay.

20. In a railway signaling system, a source of periodic currents, a circuit supplied thereby, a signal controlling relay operatively related to said circuit, and a second relay arranged to affect the action of the first relay and also in operative relation to said circuit.

40 21. In a railway signaling system, a source of periodic currents, the track rails supplied thereby, a signal controlling relay operatively related to said circuit, and a second relay arranged to affect the action of the first relay and also in operative relation to the track rails.

22. In a railway signaling system, a source of periodic currents, a circuit supplied thereby, a signal controlling relay operatively related to said circuit, and a second relay also in operative relation to said circuit and arranged to control the electro-motive force applied thereto by said source.

55 23. In a railway signaling system, a source of periodic currents, a circuit supplied thereby, a signal controlling relay operatively related to said circuit at one side of said source, and a second relay arranged to affect the action of the first relay and in operative 60 relation to said circuit at the opposite side of said source.

24. In a railway signaling system, a source of periodic currents, the track rails supplied thereby, means for confining the flow of current to a given length of said rails at each

side of said source, a relay at one end of said length of rails in operative relation therewith, a signal controlled thereby, a relay in the other end of said length of rails in operative relation therewith, and means for causing said second relay to affect the controlling action of the first relay.

70 25. In a railway signaling system, a source of periodic currents, the track rails supplied thereby, means for confining the flow of current to a given length of said rails at each side of said source, a relay at one end of said length of rails in operative relation therewith, a signal controlled thereby, a relay at the other end of said length of rails in operative relation therewith, and means for causing said second relay to control the electro-motive-force applied to the rails from said source.

80 26. In a railway signaling system, a source of periodic currents, the track rails supplied thereby, means for confining the flow of current to a given length of said rails at each side of said source, a relay at one end of said length of rails in operative relation therewith, a signal controlled thereby, a relay at the other end of said length of rails in operative relation therewith, and means for causing said second relay to affect the controlling action of the first relay and the circuit connections of its own energizing coils.

90 27. In a railway signaling system, a source of periodic currents, the track rails supplied thereby, means for confining the flow of current to a given length of said rails at each side of said source, a relay at one end of said length of rails in operative relation therewith, a signal controlled thereby, a relay at the other end of said length of rails having relatively movable coils one in operative relation with the rails, series transformers having their primaries controlled in the circuit of said source by said relay, and means for operatively relating said transformers to certain of said relay coils.

100 28. In a railway signaling system, a source of periodic currents, the track rails supplied thereby, means for confining the flow of current to a given length of said rails at each side of said source, a relay at one end of said length of rails in operative relation therewith, a signal controlled thereby, a relay at the other end of said length of rails in operative relation therewith, and means for causing said second relay to affect the controlling action of the first relay and its own sensitivity.

110 In testimony whereof, I have signed my name to this specification, in the presence of two subscribing witnesses.

CLYDE J. COLEMAN.
